**ADJUSTABLE SPRAY RATE ACTUATOR CAP
FOR A PRESSURIZED CONTAINER**

**Louis V. Nigro, Saugus, Mass., assignor to The Gillette
Company, Gillette Park, Mass.**

Filed May 10, 1972, Ser. No. 252,157

Term of patent 14 years

Int. Cl. D9—99

U.S. Cl. D9—258

FIG 1

FIG 2

FIG 3

FIG 4

FIG 5

FIG. 1 is a perspective view of an adjustable spray rate actuator cap for a pressurized container showing my new design;

FIG. 2 is a left side elevational view thereof;

FIG. 3 is a top plan view thereof;

FIG. 4 is a front elevational view thereof; and

FIG. 5 is a rear elevational view thereof.

I claim:

The ornamental design for the adjustable spray rate actuator cap for a pressurized container, as shown.
